UNITED STATES PATENT OFFICE.

WILLIAM ARTHUR FLETCHER, OF LOS ANGELES, CALIFORNIA.

COMMUNICATING CIRCUITS.

Application filed January 14, 1924. Serial No. 686,196.

This invention relates to communication circuits such as are designed for handling signals on oscillatory currents and refers particularly to an apparatus or circuit for use in receiving and rectifying radio waves.

An object of the invention is to provide an electrical system which is stable in operation. More particularly an object of the present invention is to provide a system for amplifying and rectifying oscillatory electrical energy in which a tri-electrode valve is employed and in which oscillations or regeneration may be effectively eliminated while at the same time the circuit amplifies the signal.

Various further advantages and objects of the invention will be apparent from the description of a preferred form or example of a circuit embodying the invention. For this purpose there is hereinafter described with reference to the accompanying drawing one form or example of a circuit which embodies the invention.

The drawing is an electrical diagram of the improved circuit.

Referring to the drawing, there is provided means for impressing upon the circuit the electrical energy or signals to be amplified or rectified. Said means are indicated as provided by an aerial A and a ground connection E, the leads from the aerial A and ground connection E therefor constituting the input leads to the apparatus. Between the aerial A and the ground connection E, the circuits are arranged to provide two parallel paths for the energy to be amplified or rectified. One of said paths includes a condenser C₁ and the inductance L₁. The other circuit includes the condenser C₃, inductance L₂ shunted by capacity C₂ and the phones P shunted by the capacity C₄.

There is also provided means interconnecting with the two circuits thus described for impressing a voltage thereon. Said means includes one or more tri-electrode valves V which are provided with a filament f and two other electrodes p and g. If desired, said electrodes may be a grid g and a plate p. The filament f of the valve is shown as heated by suitable means such as current from a battery B. A rheostat r is indicated for controlling the temperature of the filament f. The battery B is indicated as shunted by a potentiometer m, the moving contact of which is connected with the ground E.

The plate p is indicated as connected with one of the parallel circuits being connected to

said circuit between the condenser C₃ and inductance L₂. The grid g is connected to a grid condenser c and a grid leak g' to the other parallel circuit being connected in said circuit between the condenser C₁ and L₁.

The inductances L₁ and L₂ are shown as inductively coupled together and may be formed as a variometer in which one of the inductances is a rotor while the other is a stator. The condensers C₁ and C₃ together with the condenser C₂ are so related with the inductances L₁ and L₂ that they are adapted to bring these circuits in resonance with the signal to be received, amplified and rectified. The condenser C₁ may have, for example, a capacity of .001 microfarads. The rotor of the condenser C₁ is preferably connected with the aerial lead. The variable condensers C₂ and C₃ may in turn have capacities of .0005 microfarads and the condenser C₄ may have a capacity of .002 microfarads. The grid leak g' may have resistances from zero to five megohms.

It is understood that in place of the aerial in ground E other means for impressing upon the apparatus the signal or energy to be amplified or rectified can be employed such, for example, as a loop antenna. The circuit also may be employed in transmission or telephone work.

In the circuit thus described the phones P operate as an electro-magnetic rectifier for the signal. The signal impressed upon the circuit is at the same time amplified, the extent of amplification depending in part upon the ratio between inductances L₁ and L₂ and also upon the voltages supplied from the valve V. In operation the action of the circuit is entirely stable, no regeneration taking place and all or any of the leads may be inductively coupled in part without interference of the operation of the circuit. In order to illustrate the action of the tube V in one form of the invention the circuit was found to operate at maximum efficiency under the following conditions: the plate p of the tube was found to operate at a positive potential of 1½ volts with respect to the filament f. The grid g of the tube was found to operate at a positive potential of 5.5 volts. The current flowing through the lines connecting grid g with inductance L₁ was found to be one-half the current flowing through the line from the plate p to the inductance L₂. The current flows from the filament to both the plate p and the grid g and both of such elec-

trodes therefore operate as means for impressing a voltage across the inductances L_1 and L_2 which, in operation, serve to amplify the weak signal voltage from the antenna A.

5 While the particular form of the invention herein described is well adapted to carry out the objects of the present invention, various modifications may be made without departing from the invention and the invention is of the 10 scope set forth in the following claims.

I claim:

1. A circuit for handling oscillatory electrical energy comprising input leads, a plurality of parallel circuits interconnecting said leads, means in said circuits for inductively coupling the same together, means for bringing each circuit in resonance with the signal to be handled, a rectifier in one of said circuits, and a tri-electrode valve having its filament connected with one of said input leads through a potentiometer and having its grid and plate separately connected to portions of said parallel circuits thereby producing a potential across said inductive coupling means.
2. In a radio receiving circuit, means for impressing the signal upon two parallel circuits, means in said circuits for inductively

coupling the circuits together, means for bringing each circuit in resonance with the signal to be handled, telephone receivers operating also as a rectifier in one of said circuits, and a tri-electrode valve having two electrodes connected with said parallel circuits whereby the valve operates as a source of electrical potential which is impressed upon the inductive coupling means.

3. A circuit for handling oscillatory electrical energy comprising input leads, a plurality of parallel circuits interconnecting said leads, means in said circuits for inductively coupling the same together, means for bringing each circuit in resonance with the signal to be handled, a rectifier in one of said circuits, and a tri-electrode valve having its filament connected with one of said input leads through a potentiometer and having its grid and plate separately connected to portions of said parallel circuits thereby producing a potential across said inductive coupling means.

In testimony whereof, I have signed my name to this specification.

WILLIAM ARTHUR FLETCHER.
